UNITED STATES PATENT OFFICE.

GEORGE C. WORTMAN, OF DENVER, COLORADO.

NUT LOCK.

Application filed September 11, 1925. Serial No. 55,696.

This invention relates to improvements in the construction of railway joints and has reference more particularly to means for preventing the nut employed from turning.

In Patent No. 1,545,721 granted to me on July 14, 1925, I have shown several railway rail joints and have also shown and described means for holding the nuts from turning on the bolts. The means shown and claimed in the above identified patent is, however, too massive to be suitable for all purposes and it is the object of this invention to produce a simple inexpensive construction of railway joint and a simple means for holding the nuts from turning.

It is customary in present day railway construction to employ two ties, spaced a short distance apart, and to have the joint in the rail come between the ties. This construction makes it necessary to provide expensive saddles or bridges for the ends of the rails to rest upon which, together with the extra tie increases the cost of construction.

In the joint construction shown and described in this application, only a single wide tie is used at each joint and the abutting ends of the rails rest on a single tie plate. This makes a rigid construction that is comparatively cheap. For the purpose of preventing the nuts from loosening on the bolts that hold the fish plates to the sides of the rails I have produced a simple locking device.

My invention can be most clearly described and will be most readily understood when reference is had to the accompanying drawing in which it has been illustrated and in which:

Fig. 1 is a side elevation of a railway rail joint, a portion of the end of the tie being broken away to show the lag screw:

Fig. 2 is a section taken on line 2—2, Fig. 1, a portion of the tie being broken away to show the spike;

Figs. 3 and 4 are perspective views showing the two parts of my nut lock;

Fig. 5 is a perspective view showing the fish plate employed on one side of the rail;

Fig. 6 is a perspective view showing the angle that is applied to the outside of the joint;

Fig. 7 is a side elevation of one of the bolts employed;

Fig. 8 is a section similar to that of Fig. 2 showing a slight modification, and

Fig. 9 shows a modified locking member.

Numerals 1 and 2 represent the ends of two abutting rails and 3 the tie upon which the ends are supported. The tie is extra large and should be about ten inches wide. 60 To the upper surface of the tie I secure a tie plate 4 which differs from the ordinary tie plate in this, that it is wider, has three spike holes at each end (Fig. 1), has an undercut or grooved shoulder 5 across one 65 end and is provided on one side with a downwardly extending integral plate 6 that is adapted to be secured to the side of the tie by means of lag screws 7. The object sought to be attained by means of the plate 70 75 70 and lag screws is to secure the tie plate 4 to the tie independently of the spikes 8 so that if the spikes should loosen, the plate would be prevented from rising up without carrying the tie along with it. The ends 1 and 2 are fastened together by means of a fish plate 9 and an angle 10. This plate and angle are each provided with four holes 11 which are adapted to register with corresponding holes in the webs of the rails and are clamped to the sides of the webs by means of bolts 13. These bolts are constructed somewhat as shown in Fig. 7 and have an enlarged part 14 that, when the bolt is driven home into one of the holes 11 will 80 85 wedge tightly in the hole and will hold the bolt against turning. Before the nuts 15 are put in place onto the bolts, the member 16 of my improved locking device is put onto the bolt so that it will be clamped 90 firmly between the nut and the outer surface of the plate 9 or angle 10, as the case might be. The part 16 is of such length that its upper edge will fit against the lower surface of the rail head 17 whereby it is held against 95 turning. The lower end of locking member 16 has an integral tongue 18 cut from the material thereof and bent outwardly to an angle of 90 degrees. When the nuts have 100 been tightened, the members 16 will be held firmly and nonrotatably in the manner shown in Figs. 1 and 2. The nuts are turned until they have their sides vertical or parallel with the sides of the member 16. To 105 lock the nuts against reverse rotation, I apply to the nut a holding device 19 consisting of a metal plate having a central opening 20 of sufficient size to fit the nut 15. The lower edge of member 19 has a notch 21 which is of sufficient width to receive the 110 tongue 18 of member 16 in the manner shown most clearly in Fig. 1; after the lock-

ing member 19 has been put onto the nut the tongue 18 is bent upwardly in the manner shown in Fig. 2 so that it will not be readily removable. It is obvious that the nut cannot 5 rotate on the bolt as long as member 19 is in place thereon because it is held by member 16 that is prevented from rotation by its engagement with the lower side of head 17. When the track workers desire to remove a 10 bolt, they merely bend the tongue 18 downwards by means of a bar or hammer, after which the locking member 19 is removed. The parts 16 and 19 are so designed that they can be stamped out of sheet metal of 15 the proper thickness and strength. The plate 10 has a part 22 that extends from it at an angle and which has its edge provided with notches 231 for the reception of the spikes 8 (Figs. 2 and 6). The outer edge of 20 the angular part 22 extends into a groove 23 of the shoulder 5 so as to bind the rail to the tie plate. If desired the part 22 may be made somewhat narrower than the flange of the rail so that the edge of the latter may 25 project into the groove 23 (Fig. 8).

With my improved construction the tie plate is anchored to the tie by means of the plate 6 and the bolts 7 and the rail is anchored to the tie plate by means of the 30 groove 23 and therefore there is no tendency to separate the tie plate from the tie or to loosen the spikes. This construction is also of great advantages in maintaining the track as the trackmen by jacking up the rail also 35 raise the tie and the latter can then be tamped so as to attain the proper level.

I desire to call particular attention to my locking means which I believe to be very well adapted to railway construction as it is rugged and positive in its action and can 40 be cheaply constructed. It is customary at present to employ a spring washer underneath the nuts 15 but as these are intended merely to prevent the nut from becoming 45 loose they can be dispensed with when my locking device is used. If, for any reason, a spring washer action should be desired in addition to my lock, this can be obtained by making member 16 with cuts 24 and offsetting it in the manner shown in Fig. 9. 50

Having now described my invention, what I claim as new is:

A nut locking device adapted to be used in railway joint construction comprising, in combination, a plate having an opening 55 for the reception of a bolt, the material of said plate being spiraled about said opening so as to form a spring, said plate being further adapted to be clamped in place underneath a nut, a portion of said plate being 60 bent outwardly so as to form a tongue, a second plate having an opening of the proper size and shape to receive a nut and an other opening adapted to receive said tongue whereby when said first mentioned plate is 65 clamped beneath the nut and the second plate secured about the nut and in such a position that the tongue and opening cooperate the nut will be held against rotation.

In testimony whereof I affix my signature.

GEORGE C. WORTMAN.
